CLAIM

The ornamental design for a camera module, as shown and described.

DESCRIPTION

FIG. 1 is a top and front perspective view of a first embodiment of a camera module showing our new design; FIG. 2 is a top plan view thereof; FIG. 3 is a bottom plan view thereof; FIG. 4 is a right side elevation view thereof; FIG. 5 is a left side elevation view thereof; FIG. 6 is a front elevation view thereof; FIG. 7 is a back elevation view thereof; FIG. 8 is a bottom and front perspective view thereof; FIG. 9 is a top and back perspective view thereof; FIG. 10 is a bottom and back perspective view thereof; FIG. 11 is a top and front perspective view thereof; shown in condition of use with a cable disclosed in broken lines to illustrate an environment;

FIG. 12 is a bottom and back perspective view thereof; FIG. 13 is a top and front perspective view of a second embodiment of a camera module; FIG. 14 is a top plan view thereof; FIG. 15 is a bottom plan view thereof; FIG. 16 is a right side elevation view thereof; FIG. 17 is a left side elevation view thereof; FIG. 18 is a front elevation view thereof; and, FIG. 19 is a back elevation view thereof.

The broken lines depict portions of the camera module in which the design is embodied that form no part of the claimed design. The broken lines showing a cable in FIGS. 11–12 represent environmental structure and form no part of the claimed design.
